UNITED STATES PATENT OFFICE.

ROWLAND ROBINSON HAZARD, OF NEW YORK, N. Y.

UNDERGROUND-RAILWAY STRUCTURE.

SPECIFICATION forming part of Letters Patent No. 314,021, dated March 17, 1885.

Application filed July 11, 1884. (No model.) Patented in England August 6, 1884, No. 11,000, and in France August 9, 1884, No. 151,139.

To all whom it may concern:

Be it known that I, ROWLAND ROBINSON HAZARD, a citizen of the United States, residing in the city, county, and State of New York, 5 have invented an Improvement in Underground-Railway Structures, of which the following is a specification.

The objects of my invention are to economize space in the construction of underground railway structures and at the same time to secure thorough ventilation; also to largely diminish in such a structure the noise occasioned by the passage of trains. These several objects I accomplish by the means hereinafter 15 fully described and claimed.

In the accompanying drawings, Figure 1 is a transverse section of a series of railway-tunnels constructed in accordance with my invention, and Fig. 2 is a horizontal cross-section 20 of a column and panels between the tunnels. Fig. 3 is a horizontal cross-section of a column, showing the deflecting-plates secured to the same. Fig. 4 is an elevation on a reduced scale, showing parts of two columns 25 and the deflecting-plate extending from one to the other.

An underground-railway structure to meet the demands of a populous city—such, for instance, as New York—must be provided with 30 four tracks—two for express and two for accommodation trains. It is a fact that in the narrow streets of a city there is not sufficient space to construct side by side four single-track tunnels with the usual thick walls intervening. A single tunnel provided with four tracks could be constructed in some streets, but in this construction it is not possible to obtain good and thorough ventilation. To secure this it is necessary to provide a separate 35 tunnel for each track, and in order that the aggregate width of the four tunnels may not be greater than available, I construct the same in the following manner: Between the tracks, and at suitable intervals, (preferably of four 40 or five feet,) supporting posts or columns, as A, of iron or steel, are erected, of any convenient form in cross-section, but preferably of the form shown in Fig. 2, and of a width in cross-section of about four inches. These col-

umns, together with the similar columns of 50 the outer walls of the tunnels, support the girders B, which carry the roof or roadway of the street, in any approved manner, and are calculated to bear the maximum strain. In the space between the columns are secured, 55 by any suitable means, sheets, plates, or panels C, of strong but thin material—such, for instance, as iron or steel plates, wood, heavy paper boards, or leather—in fact, any material sufficiently strong not to be broken or 60 ruptured by the pressure of the air during the passage of trains. I prefer, however, to use a non-resonant material, and of the many materials of this nature I prefer to use one consisting of a woven metallic material similar to heavy iron-wire fabric, grating, or lattice-work, overlaid on one or both sides by flax or other vegetable or mineral fiber covered by oxidized or solidified vegetable oil, and formed into flat panels, sheets, or shapes 65 70 by hydraulic or other pressure. Instead of oxidized or solidified vegetable oil, pure or vulcanized india-rubber or gutta-percha may be used, or lead, zinc, or earths mixed with oil may be employed. Panels or sheets so 75 formed are stiff, will not become fragmentary by collision, are non-resonant, and damp-proof. They may be readily fastened, and will be relatively cheap. The woven metallic material furnishes the requisite stiffness and 80 unbreakableness, and this being its function it is evident that the material need not be woven; but the wires, rods, or bars of which it is composed may be tied, riveted, or otherwise fastened together. The flax fiber covered 85 by oxidized or solidified oil imparts a non-resonant character to the panels or sheets, assists to make them unbreakable, and renders them proof against dampness. To secure these ends, I prefer to use flax fiber treated as 90 described; but any other material serving the same purpose may be employed. These plates, sheets, or panels are preferably made of a size (say four by ten feet) to fit the spaces between the columns, and may be readily fastened at 95 the sides by bolts to the extended flange of one of the angle irons of each column, as shown in Fig. 2, or otherwise, but preferably with

clamping bars and bolts. The sheets or panels may be secured at the top and bottom, or they may be left free, with or without re-enforcement. I do not limit myself to any particular means of fastening the panels to the columns, as any suitable means may be used.

The series of columns with the panels secured thereto form a very thin and at the same time a very strong wall between the tunnels, enabling four tunnels to be constructed side by side in narrow streets, and completely separating one tunnel from another, so that a train in motion may act similarly to a piston in an open cylinder—*i. e.*, may displace the air—whereby good ventilation is obtained. Further, when the panels are constructed of a non-resonant material according to the second part of my invention, the noise which would be caused by the passage of a train through a resonant tunnel is obviated.

A continuous deflecting-plate, as D, is secured to said columns, and prevents injury to the same by deflecting any blow imparted by a carriage in case of accident or otherwise.

It is evident that my invention is also applicable to less or more than four adjacent tunnels, as heretofore described, and I do not, therefore, desire to limit myself to any particular number of adjacent tunnels.

In the drawings I have shown a new disposition and location of water-pipes, sewers, gas-mains, steam-heating pipes, electric conduits, &c., for the purpose of compensating municipal and vested rights, and replacing plant pre-occupying the space taken for the tunnels; but I make no claim herein to the novel features thereof.

What I claim, and desire to secure by Letters Patent of the United States, is—

1. An underground-railway structure constructed with a thin wall between its tracks, whereby the space necessarily occupied is reduced to a minimum and proper ventilation obtained, substantially as described. 40

2. An underground-railway structure constructed with a thin wall of non-resonant material between its tracks, whereby the space necessarily occupied is reduced to a minimum, proper ventilation obtained, and the noise caused by the passage of trains is obviated. 45

3. An underground-railway structure constructed with a series of columns between its tracks, and a series of panels in the spaces between said columns, substantially as described. 50

4. An underground-railway structure constructed with a series of columns between its tracks, and a series of panels of non-resonant material in the spaces between said columns, substantially as described. 55

5. An underground-railway structure constructed with a series of columns between its tracks, and provided with deflecting-plates, substantially as described.

In testimony whereof I have hereunto set my hand in the presence of two subscribing witnesses. 60

ROWLAND ROBINSON HAZARD.
